UNITED STATES PATENT OFFICE

PHILIP MAZER, OF BROOKLYN, NEW YORK

DEVICE FOR TREATING FABRICS AND THE LIKE

Application filed March 4, 1931. Serial No. 520,000.

My invention relates to material and devices adapted to be used for restoring to a cloth or fabric the original dull finish that it has lost by a continued abrasion of its surface 5 after dust or other dirt particles have collected thereon. In its broadest aspect, the invention comprises the provision of a material for effecting this result in a form and in combination with means of operation 10 which is as efficient in its use as it is simple in form. More particularly, the invention contemplates the provision of a device which may be used for removing the familiar "shine" that is acquired by fabric, for instance, at the seat of the trousers of men's suits, when such fabric has been worn for 15 any length of time.

This application is in part a continuation of an application, Serial No. 451,307, filed 20 by me, which application discloses an electric motor actuated apparatus with which certain of the specific embodiments of my present invention are adapted to be used. Reference is made to said copending application for a clear understanding of the structure and operation of the apparatus to 25 which such specific embodiments, hereinafter described, may be applied.

In said application, I have described an 30 apparatus comprising a casing, a motor housed therein, a drum connected to said motor, and a cylinder mounted on the drum and a pad of steel wool secured to the surface of the cylinder. Such pad of steel wool 35 and the cylinder to which it is applied, comprise an operative element of the apparatus and form one of the embodiments illustrating the present invention.

I have discovered that a more perfect result 40 can be obtained by the use, in combination with such cylinder, or other supporting body, of a mass of steel wool which has been spun into a form which, for the lack of a better descriptive term, I shall hereinafter refer to 45 as a "rope". In accordance with my invention, therefore, a mass of steel wool in the form of long strands of steel shavings, is spun into a rope by the twisting of a large number of such strands. A straight and 50 elongated mass of strands of steel wool is merely grasped by suitable means at the two ends thereof and twisted over and over again until the elongated body has been spun into the form of a rope of steel wool. Such rope of steel wool is then secured, in the manner 55 to be described, to the hollow cylinder which is to be slipped over the drum of the apparatus shown in said copending application, or to any other supporting body, for instance, a brush structure, also hereinafter described. 60

Particular embodiments of my invention are illustrated in the accompanying drawings, in which Fig. 1 shows a pad of steel wool applied to a cylinder comprising, together, the operative element of the apparatus shown 65 and described in my application, Serial No. 451,307; Fig. 2 illustrates the form of cylinder to which a pad of steel wool is to be applied; Fig. 3 is a longitudinal section through the drum having the cylinder and 70 steel wool pad mounted thereon; Fig. 4 is an end view of the assembly shown in Fig. 3; Fig. 5 shows the steel wool applied to the cylinder in the form of a rope, spun of steel wool; Fig. 6 illustrates the form of cylinder 75 to which the steel wool rope is applied; Fig. 7 is a section along line 7—7 of Fig. 5; Fig. 8 illustrates a form of brush as a supporting body for the steel wool rope; Fig. 9 is a bottom view of the brush with the rope of 80 steel wool secured to the plate member thereof; Fig. 10 is a plan view of the plate member of the brush in its flat position without the steel wool and before it is secured in position within the brush body; and Fig. 11 85 is a section along line 11—11 of Fig. 8.

Referring more particularly to the drawings, in which similar reference characters identify similar parts in the several views, the drum 16 has mounted thereon a cylinder 90 17 of tin or other suitable sheet metal having attached thereto, and surrounding the same, a pad of steel wool 18. The cylinder 17 is shown independently of the drum upon which it is mounted, in Fig. 2, while the 95 manner of the attachment of the pad of steel wool 18 thereto is illustrated in Fig. 1. As shown in such figure, the steel wool, after being wound upon the cylinder, is firmly secured thereto by fine wire 19, one end of which 100

may be fastened to the cylinder by catching it in a slit 20 provided for such purpose at one end of such cylinder; the other end of such wire, after being wound around the 5 steel wool so as to be embedded therein and thus secure the same rigidly to the cylinder, may be fastened to the other end of the cylinder by catching the same in slit 21 as will appear clearly from an inspection of the figure. In order to insure a secure binding of the pad of steel wool to the surface of the cylinder 17 I provide irregular prongs 22 distributed throughout the surface of such cylinder for grasping the fibres of the steel 10 wool pad, and triangular cuts 23, the surfaces of which, when raised from the plane of the cylinder 17 will act as anchoring elements for the end of the pad when such pad is first rolled over the cylinder 17.

15 20 A second embodiment of my invention is illustrated in Figs. 5 to 7 in which the drum 24 has mounted thereon a cylinder 25 of tin or other suitable sheet metal, the cylinder being provided with an angled slot 26 adapted 25 to be engaged by a pin 27 protruding from the surface of the drum 24, so that the cylinder 25 may be secured on said drum by slipping the same over such drum and giving it a partial turn to lock the pin 27 of the drum 30 within the transverse section of the angled slot 26. About the cylinder 25 is wound a rope of steel wool 28 which is anchored at one end thereof by a prong 29 cut from the surface of the cylinder and protruding therefrom between which and the surface of the cylinder the end of the steel wool rope is 35 clamped. After the rope of steel wool has been wound about the cylinder 25 in the manner illustrated in Fig. 5 the other end of such 40 rope is anchored by passing the same under a prong 30 provided at the other end of the cylinder 25.

In each of the above described modifications the drum is provided at one end thereof 45 with a pulley 31 over which the belt or similar driving connection between the motor and such drum may be passed.

In Figs. 6 to 11, I have illustrated a still further embodiment of my invention in which 50 the supporting body for the steel wool comprises a device in the form of a brush, preferably made of metal. In such embodiment the rope of steel wool is wound upon a plate of sheet metal or other suitable material 32 55 which is shown in outline in Fig. 10. Such plate has its end portions cut to present successive arcuate recesses 33, 33, which provide a seat for the rope of steel wool wound about the plate. The plate has cut out at one corner thereof a tongue 34 between which and the surface of the plate one end of the rope of steel wool 35 is clamped, the rope being 60 then passed successively over the surface of the plate 32 longitudinally thereof, the bends 65 in said rope, as the same is passed over the

edge of the plate 32, being accommodated within the arcuate slots 33, 33. When the entire plate has thus been covered with a winding of steel wool rope, the end of such rope is clamped between a tongue 36, provided at a diagonally opposite corner of the plate, and the surface of such plate. 70

After the steel wool rope has thus been wound about one of the ends of said plate, the plate is positioned within the curved seat 75 37 formed by the end of the brush body and the plate is bent into the form of an arc so that its other end may be secured within the curved seat 39 at the opposite end of the brush body. The brush body comprises a 80 rigid flat metal plate 40 from the center of which extends downwardly angle irons 41 and 42 which supply the rigidity to the brush necessary in the course of its use, when pressure is applied to the plate 40 in the course of 85 passing the brush over the fabric to be treated. Depending from the plate 40 on each side thereof is a metal plate 43 forming the sides of the brush, a greater portion of which is indented as shown at 44, (Fig. 11) to provide surfaces whereby the entire brush may 90 be grasped by the hand when such brush is passed over the fabric being treated.

The application of the steel wool to the various devices illustrated in the form of a 95 rope into which it has been spun has certain advantages which prompt me to describe such form as my preferred one. It will be readily appreciated that the steel wool provided in the form of a rope has greater wearing qualities than has a pad of steel wool indiscriminately compressed into a mass. Furthermore as the steel wool wears, it will wear uniformly throughout the surface of the rope, still 100 maintaining the form of a rope. In the embodiment illustrated in Figs. 8 to 11, it will also be evident that when one side of the steel wool is worn down to an appreciable extent it will only be necessary to remove the plate 32 about which the steel wool rope is 105 wound, from the brush, reverse the plate, and replace it into the brush with the opposite side facing outwardly so that an entirely new surface of steel wool is presented to the fabric or cloth being treated. 110

115 While I have described specific embodiments of my invention it is obvious that various modifications therein, particularly in the arrangement of parts, may be made without departing from my invention.

I claim:

1. The combination with a brush body, of a flexible metal plate removably applied to said body and having a rope of steel wool wound thereon in contact with the opposite 120 surfaces of said plate.

125 2. The combination claimed in claim 1 in which the brush body has its opposite ends curved to provide channels for receiving the ends of the flexible metal plate. 130

3. The combination claimed in claim 1 in which the flexible metal plate is provided throughout its end surfaces with arcuate slots adapted to receive the steel wool rope.
4. The combination claimed in claim 1 in which the flexible metal plate is provided with tongues cut out of, and protruding from, the surface of said plate, for anchoring the ends of the steel wool rope to said plate.

PHILIP MAZER.
